BROOCH

Malle Little Russell, Philadelphia, Pa.

Application May 19, 1938, Serial No. 208,884

3 Claims. (Cl. 24—87)

This invention relates to a brooch, and more particularly to an improved means for fastening a brooch or like article to a garment.

It is well known that brooches, being articles of personal adornment, are adapted to be fastened by means of pins to the most expensive and delicate types of textile fabrics. Heretofore, articles of this kind have been commonly subject to the objectionable features of causing injury and inconvenience in attaching the brooch to and detaching it from the fabric. The injury to the fabric has for the most part been caused by the fabric catching between the pins by which the brooch is fastened to the fabric and the body of the brooch and the inconvenience from the use of such an article has arisen from the effort necessary to be expended in attempting to disengage without injury to the threads of the fabric a brooch which has been caught in such a manner.

In my prior Patents Nos. 757,756 and 1,405,445 I have shown a securing means for brooches, buckles, etc., which overcomes the faults incident to the use of pin fastening means of the character referred to. In such prior patents I have disclosed fastening means in the form of hooked pin elements having spaced points extending toward each other whereby the point at one side of the device may be inserted in the garment and the buckle or the like moved with respect to the garment in the direction of the other point or points, whereupon the latter may be hooked into the garment.

These devices were substantial improvements over conventional pin structures but they possessed the disadvantage of having substantially U- or J-shaped pin members which effectively held the devices in position, but the cloth through which the pins were inserted sometimes passed around the loops of the pin and made it somewhat difficult to remove them. Unless care was used in removing a buckle or the like employing the structures referred to, injury to the fabric might result as in the case of conventional pin structures.

Accordingly, the principal object of this invention is to provide means for fastening a brooch or the like to fabric, which will materially diminish the possibility of injury to the fabric.

A further object is to provide a brooch with fastening means which will enable the brooch to be detached from the fabric with a minimum of effort.

A further object is to provide a brooch with fastening means which positively prevents the

danger of catching the fabric between the back of the brooch and the fastening means.

A further object is to provide a brooch with fastening means which will hold the back of the brooch in close proximity to the fabric to which it is attached.

Other objects and advantages of the invention will become apparent during the course of the following description.

In the drawing I have shown several embodiments of the invention. In this showing:

Figure 1 is a plan view of the back face of a brooch provided with fastening means.

Figure 2 is a sectional view taken along the line 2—2 of Figure 1 showing the brooch attached to a piece of fabric.

Figure 3 is a perspective view of one set of the fastening means.

Figure 4 is a perspective view of a modified embodiment of the invention, and,

Figure 5 is a perspective view of a further modification.

Referring to Figure 1, the numeral 10 designates the body member of the device such as a brooch, provided with identical fastening devices 11 and 12 located at diametrically opposite sides of the brooch. The identical fastening devices 11 and 12 are more clearly shown in the perspective view in Figure 3, and will be presently described in detail.

A suitably formed metallic strip 13 having a flat surface 14 is provided for attachment to the brooch 10 at suitable points by soldering or any other means. Obviously, the strip 13 could be made integral with the back of the brooch. The strip 13 is provided with abutments 15 formed thereon or integral therewith. Needle-like garment fastening devices 16 are provided for fastening the brooch to a garment and protrudes from the abutments 15. The ends of the abutments remote from the strip 13 are preferably formed in the shape of a sphere, and the garment pins 16 are connected to the spherical portion of the abutment centrally thereof in order that the abutment will diverge abruptly from the shank 40 of the garment fastening devices 16.

Referring to Figure 4, I have shown my fastening devices 16 applied to a brooch having a body member 17 in the form of a corsage holder having a semi-circular portion provided with a pin 18 centrally thereof for holding the stems of flowers (not shown). It will be noted that abutments 15 are preferably attached directly to flat surfaces 19 forming the ends of the body member or corsage holder 17 without the use of a strip 13.

In Figure 5, I have shown a modification of the attaching means. In this showing an abutment structure 20 is employed wherein the end of each abutment remote from the brooch is of a cylindrical shape and the fastening devices 16 are connected thereto so as to intersect the axis of the cylindrical portion of the abutment. In Figures 4 and 5 it will be noted that the needle-like garment fasteners 16 are substantially parallel to the common plane of the flat surfaces 19 of the body member of the device, and that the fasteners at opposite sides of the device point toward each other.

Referring to Figure 2 wherein the brooch 10 is shown attached to a piece of fabric 21, it will be noted that the needle-like garment fastener 16 terminates at the abrupt enlargement provided by the spherical portion of the abutment 15 to effectively prevent movement of the fabric beyond or over the abutment 15. Accordingly, the needle-like garment fastener 16 may be inserted between the threads of the fabric but the abutment 15 will prevent the fabric from being caught at any point between any of the fasteners and the body portion of the brooch 10. Accordingly, it will be obvious that the brooch 10 may be disengaged in the fabric 21 without injury to the threads of the fabric.

Regardless of the type of abutment used, there will be provided a rounded surface 22 spaced from the flat surface 14 and beyond which the fabric cannot pass when the pointed members 16 are inserted thereinto. The rounding of the abutments 15 and 20 in this manner eliminates any sharp edges engaging the fabric to cause injury thereto. Moreover, since the fabric, where pierced by the members 16, cannot pass beyond the butt ends of the members 16, the portion of the fabric between the abutments will be held in proximity to the members 16. Therefore, these members will lie against the fabric, thus rendering it substantially impossible for the points of the members 16 to stick into the skin of the wearer. It also will be noted that the portions of the fabric which pass over the abutments will be supported thereby to space the members 16 from the wearer and thus assist in protecting the wearer from injury.

It has been found desirable to place equal numbers of garment fasteners 16 at opposite sides of the brooch with the fasteners 16 lying in a common plane substantially parallel to the flat surfaces 14 or 19 and with the ends of each fastener 16 in substantially direct alignment with and projecting toward a similarly positioned fastener on the opposite side of the brooch. With this construction the brooch is very easily attached to and detached from the fabric garment.

From the foregoing, it will be apparent that I have provided means for fastening a brooch to fabric which effectively prevents injury to the fabric and by so doing minimizes the amount of effort necessary to detach the brooch from the fabric.

It is to be understood that the forms of the invention herewith shown and described are to be taken as preferred examples of the same and that various changes in the shape, size and arrangement of parts may be resorted to without

departing from the spirit of the invention or the scope of the subjoined claims.

I claim:

1. A device of the character described comprising a body member, abutments fixed to one face of said body member adjacent opposite edges thereof and projecting laterally therefrom, a relatively short substantially straight needle-like element carried by each abutment, said elements having their pointed ends extending toward and substantially in alignment with each other and spaced a substantial distance apart, said elements lying in a common plane substantially parallel to the portions of said body member to which said abutments are fixed and having their remote ends fixed to portions of said abutments which face toward each other, each abutment having a continuous smooth surface diverging sharply in all directions from the needle-like element fixed thereto to present a smooth abrupt enlargement to fabric impaled on said elements to prevent the fabric from sliding over said abutments and from becoming abraded or otherwise injured thereby.

2. A device of the character described comprising a body member, a pair of substantially spherical abutments carried by and arranged adjacent opposite edges of and spaced from one face of said body member, a relatively short needle-like element fixed to and protruding from each abutment substantially radially thereof and lying substantially in a common plane spaced from and parallel to the adjacent portions of said body member, each of said elements projecting toward the other element in substantially direct alignment therewith and terminating a substantial distance therefrom, the substantially spherical shape of each abutment providing a smooth continuous surface diverging from the corresponding element and presenting an abrupt enlargement to a fabric impaled on the corresponding element to prevent the fabric from sliding over either of said spherical abutments, said smooth surface extending to a sufficient distance from the point of connection of said elements to said abutments to prevent abrasion or other injury to the fabric.

3. A device of the character described comprising a body member, a pair of parallel substantially cylindrical abutments arranged adjacent opposite edges of one face of said body member and carried thereby, a plurality of relatively short parallel needle-like elements fixed to and projecting from each abutment substantially radially thereof, said elements lying substantially in a horizontal plane spaced from and parallel to the adjacent portions of said body member, each element of each abutment projecting toward and being substantially aligned with an element of the other abutment and terminating a substantial distance therefrom, each abutment presenting a smooth curved surface diverging sharply from each of the associated elements at their points of connection therewith to present an abrupt enlargement to a fabric impaled on said elements to prevent the fabric from sliding over said abutments, said smooth surface extending to a sufficient distance from such points of connection to prevent abrasion or other injury to the fabric.

MALLE LITTLE RUSSELL.
